UNITED STATES PATENT OFFICE.

BRUCE CLARK WHITE AND JAMES A. BOYD, OF CHICAGO, ILLINOIS, AS-SIGNOR TO CHISHOLM, BOYD & WHITE, OF SAME PLACE.

BRICK-MACHINE.

SPECIFICATION forming part of Letters Patent No. 429,296, dated June 3, 1890.

Application filed January 2, 1889. Serial No. 295,160. (No model.)

To all whom it may concern:

Be it known that we, BRUCE CLARK WHITE and JAMES A. BOYD, of Chicago, in the county of Cook and State of Illinois, have invented 5 certain new and useful Improvements in Brick-Machines; and we do hereby declare that the following is a full, clear, and exact description thereof, reference being had to the accompanying drawings, and to the letters of 10 reference marked thereon, which form a part of this specification.

This invention relates to that class of machines for making brick in which the clay to form the bricks is compressed within a 15 mold by means of two opposing plungers, which are moved toward each other in compressing the brick and are moved to accomplish the discharge of the finished brick from the mold, and are also moved within the mold 20 during the act of compressing the brick in such manner as to give the brick smooth or polished edges.

The invention embraces more particularly improvements in a machine illustrated in a 25 prior application made by B. C. White and James A. Boyd, April 10, 1888, Serial No. 270,210.

In the accompanying drawings, illustrating 30 our invention, Figure 1 is a central vertical section of a machine embodying our invention. Fig. 2 is a vertical cross-section thereof, taken upon line 2 2 of Fig. 1. Fig. 3 is a detail plan section taken upon line 3 3 of Fig. 1. Fig. 4 is a detail section taken upon line 35 4 4 of Fig. 1. Fig. 5 is a detail elevation of a device for adjusting the depth of the mold at the time of filling the same, hereinafter described. Figs. 6, 7, and 8 are detail views, illustrating the operation of the devices for 40 actuating the lower plunger. Fig. 9 is a detail view of one of the parts shown in Fig. 2. Figs. 10 and 11 illustrate in side and end elevations modified forms of construction in the devices for adjusting the depth of the mold 45 at the time of filling the same. Figs. 12 and 13 are detail views of modified forms of construction, illustrating the operation of the devices for actuating the lower plunger.

The main frame of the machine herein 50 illustrated as embodying our invention consists of two heavy vertical frame-plates A A,

arranged parallel with each other at opposite sides of the machine and attached to a massive base A', which connects the said frame-plates at the bottom of the machine. The 55 said frame-plates A A embrace two vertical standards A² A², affording bearings for the vertically-movable parts of the machine, and said frame-plates are connected with each other at the top of the frame by a horizontal 60 cross-girt A³.

B is a mold-table, which is located at a convenient distance above the base A', and is arranged horizontally between and bolted at its ends to the vertical standards A² A² of the 65 frame. Within the said mold-table are located the molds C C, of which the machine shown is provided with three. Said mold-table is herein shown as comprising two separate castings B' B², Fig. 3, located in front 70 and rear of the molds, which latter are formed by means of inwardly-projecting parts B³ B³, cast upon the front and rear portions B' B² of the table and meeting at the center line of the table. The castings B' B² are held together by means of horizontal bolts b b, passing through said casting between the molds and at the ends of the castings, in the manner shown.

The castings B B are secured to the frame-standards A² A² by means of horizontal bolts b' b', inserted through wings b³ b³ at the ends of the castings B' B² and through said standards. Said parts B' B² of the mold-table, for the purpose of giving a rigid and unyielding 8c support to the said table and to prevent the same from springing or yielding in its center under the heavy strain incident to pressing the brick, are provided with vertical webs B⁶ B⁷, which extend downwardly to and rest or 90 bear throughout their full length upon the frame-base A'. The said webs are desirably provided with horizontal flanges at their lower edges, through which flanges and the base are inserted bolts b⁶ b⁷, affording a rigid connection between the parts. The webs B⁶ B⁷, bolted at the frame-base in the manner shown, serve to transmit to said base a part 95 of the strain coming upon the table, and at the same time hold the adjacent parts rigidly and 100 strongly from either lateral or vertical displacement when the machine is in action.

Said webs B^6 B^7 are provided with openings at points beneath the molds in the manner shown, to afford access to the lower plungers for supplying steam thereto and for reaching 5 the adjusting devices connected therewith, which are hereinafter described.

To afford a strong connection between the mold-table and the frame-standards A^2 , the latter are provided with notches or mortises a 10, a , Fig. 2, at their inner faces, within which notches or mortises the ends of the castings B' B^2 are inserted, and within which they are held by means of the bolts b' b' . The castings B' B^2 in the particular construction 15 shown form the parts of the mold-table immediately adjacent to the molds. Horizontal extensions of said table at the front and rear of the molds, for the purpose of supporting the feeding devices for the clay and the finished bricks, are formed by a horizontal 20 plate B^4 at the front of the molds, which plate is bolted to the casting B' in the manner shown, and by a second horizontal plate B^5 , which is located at the rear of the casting B^2 25 and is sustained by attachment to the horizontal parts of the frame-plates in the manner illustrated.

D D are a series of plungers constructed to enter and slide in the upper parts of the 30 molds C C , said plungers being attached to a horizontal cross-head D' , located above the mold-table B .

E E are lower plungers constructed to slide in molds C C and attached to a single rigid 35 cross-head E' , located beneath said mold-table.

F F are two heavy vertical bars, which are mounted in guide-surfaces a' a' , formed in the inner faces of the frame-standards A^2 A^2 , 40 and engaging corresponding guide-surfaces upon the bars. Said bars extend from a point near the bottom of the machine, through the ends of the mold-table B , to points near the upper ends of the frame-standards A^2 A^2 . The bars are held or guided at two points 45 only—one at the top of the frame-standards and the other just above the mold-table—the guide-surfaces a' a' being relatively short and located at these places only.

G G' are toggle-arms, which are pivoted, respectively, to the upper ends of the slide-bars F F and the upper cross-head D' . The upper end of the upper toggle-arm G is desirably made the full width of the space between the 55 slide-bars F F , as clearly shown in Figs. 1 and 2, and said toggle-arm is pivotally connected with the said slide-bars by means of a heavy pivot-pin G^2 , fixed at its ends in the slide-bars and extending through a long bearing-aperture in the toggle-arm. The lower toggle-arm G' is constructed to enter a recess in the upper surface of the cross-head D' , and is pivotally connected with the latter by means of a pivot-pin G^3 , inserted through bearing-aperture in opposite ends of said cross-head and in the lower end of said toggle-arm. The toggle-arms G G' are pivotally connected with

each other by means of a heavy pin G^4 , inserted through the overlapping forked ends of said toggle-arms, said pin being also 70 adapted to engage a heavy beam H , by which power is applied to the toggle-arms. Said beam engages the center of the pin G^4 , and the toggle-arms are centrally recessed to afford space for the entrance of the end of said beam between their parts in bearing with the pin in the manner illustrated in the drawings.

I is a heavy crank-shaft mounted in bearings in the frame-plates A A , said crank-shaft being located approximately in the same horizontal plane with the pivot-pin G^4 and some distance to the rear of the toggle-arms. Said crank-shaft is provided with a heavy crank-pin I' , with which the beam H 85 is engaged. The said crank-shaft I is so disposed with relation to the toggle-arms G G' that in the rotation of said shaft said toggle-arms will be alternately straightened out and flexed by the action of the crank and beam. Said parts are so disposed, furthermore, that the toggle-arms will be straightened out or brought into alignment with each other at the time the crank-pin is at the extreme limit of its throw away from the toggle-arms.

J is a pin or shaft mounted horizontally upon the frame-plates A A , beneath the beam H , and having its ends secured in two hubs a^4 a^4 upon the frame-plates. Upon said shaft 100 are mounted two vertically-arranged oscillating arms J' J' , which are recessed at their upper ends and are adapted to engage the ends of the heavy pins H^1 and H^2 , which are secured in the beam H between its ends and 105 preferably nearer that end of the beam engaged with the toggles G G' . The rocking arms J' J' engage the beam H as the latter is moved in the turning of the crank-shaft and serve as fulcrums or point of support for the 110 beam, so that the latter operates as it is moved by the crank-shaft to raise and lower the toggle-arms, the slide-bars, the upper and lower cross-head, and the plungers. A vertical movement is thus given to the upper 115 and lower plungers for discharging the brick from the mold and for moving the brick within the mold to smooth and polish the edges of the brick during the compression of the same and to enable the clay to be fed to 120 the molds, as will hereinafter more fully appear.

K is a heavy drive-wheel affixed to the shaft 125 I outside of the frame-plate A . Said drive-wheel is provided with peripheral cogs which engage a pinion K' , mounted upon a stud K^2 , located at the rear part of the frame, said stud having upon it a belt-pulley K^3 , over which may be placed a driving-belt for transmitting power to the machine.

L is a sliding feed-box which rests and slides upon the top of the mold-table B^5 at the rear side of the molds. Said feed-box consists of a horizontal plate or casting pro-

vided at its end adjacent to the molds with rectangular openings L' L', corresponding in horizontal dimensions and in number with the molds C C C. The openings L' L' are closed at their bottoms by the mold-table upon which the feed-box rests, except when said feed-box is moved forward to bring said openings over the molds.

M is a stationary feed-hopper located over the sliding feed-box L at a point adjacent to the upper plungers D. Said feed-box L has a horizontal reciprocatory motion through a distance sufficient to carry the openings L' L' over the molds C C and under the feed-hopper. When beneath the hopper, the feed-box receives material from the same, and such material is discharged into the molds when the feed-box is moved forward.

At the rear of the receptacle L' L' the feed-box is provided with a smooth horizontal top surface L⁴, which extends the full width of the feed-box and is somewhat longer than the distance through which the latter travels in operation. Said surface L⁴ is for the purpose of supporting material within the hopper during the time the feed-box is being moved forwardly to carry the clay to the mold.

N is a rock-shaft mounted at its ends in the frame-plates A A and provided with an upwardly-extending arm N', which engages a cam K⁴ upon the drive-wheel K, and with two depending arms N² N², which are connected by pitmen N³ N³ with the opposite sides of the feed-box, in the manner clearly shown in the drawings, Figs. 1 and 2. The cam K⁴ is a grooved cam, adapted to engage a roller n upon the arm N', and is so shaped as to advance the feed-box over the molds at the time the upper plunger is lifted above the same.

The construction and operation of the main parts of the machine above described are substantially the same as that of the corresponding parts of the machine shown in said prior application, Serial No. 270,210, the compression of the brick being produced solely by the action of the toggle-arms operating through the medium of the slide-bars F F in the upper and lower cross-heads D' E', while the vertical position of the plungers within the molds is determined by the action of the beam H and rocking arms J' J', except when the cross-heads carrying the plungers bear against their stops. As shown in said application, a roller is placed beneath the beam and is adapted to engage the latter in its forward movement, by which the plungers are lifted in ejecting the brick from the mold, said roller engaging the beam at a point nearer the crank-shaft I' than the pin H', so that after the fulcrum of the lever has been shifted from the rocking arms and pin to the roller a relatively rapid and extended upward movement of the plungers is accomplished. As herein shown, however, any such roller is absent, and the beam H is provided, between the pin H' and the crank-pin, with

the second pin H², arranged parallel with the pin H', while the rocking arm J' is made in the form of the segment of a cog-wheel and is provided with two notches j j', adapted to respectively engage the pins H' H². By this construction the same result is produced as obtained by the roller in a more simple manner, it being entirely obvious that as the beam is carried forward to flex the toggle-arms and lift the plungers the fulcrum of the beam will be shifted from the pin H' to the pin H², so that the beam will act in lifting the plungers at first with greater power and slower motion, and afterward with less power and greater speed. In the particular construction of the parts last referred to, as herein illustrated, the pins H² H' are connected by a bridge-piece H³, which rides upon the tooth projection j² between the notches j and j', so that the downward pressure of the beam will be transmitted smoothly and without jar from the pin H' to the pin H². The rocking arm J' is also desirably provided with an arm or prong j³ at the rear of the notch to insure the proper engagement of the pin H² with the said notch when the fulcrum of the lever is shifted from one notch to the other. In view of the advantages obtained by the use of the segmental rocking lever in connection with a plurality of pins in the beam as a means of shifting the fulcrum of the same, this construction is herein claimed as part of our invention.

As a further improvement, the machine shown in the drawings embraces certain novel features of construction in the means connecting the lower plungers with the lower cross-head, by which the same are operated. Such devices are made as follows: The said lower plungers E E, instead of being positively or rigidly attached to the lower cross-head E', are vertically movable with relation to the said lower cross-head, and said plungers are sustained from the cross-head by means of weighted levers or equivalent springs engaging the cross-head and pressing upwardly against the plungers. By this construction the said lower plungers in certain positions of the lower cross-head may be moved vertically within the mold independently of the position of the cross-head. The said plungers are, however, provided with surfaces or shoulders adapted to engage the cross-head in the upward movement of the latter, so that the plungers will be positively lifted in compressing the brick. In the particular construction of these parts illustrated in the drawings the plungers E are provided with vertical depending stems E², which pass through centrally-arranged apertures in the upper part of the cross-head E', which is desirably made hollow and of inverted-U shape in cross-sectional form. At its lower end the stem E² is held and guided in a vertical tubular guide O, attached to and supported upon the frame-base A'. At a short distance below the plunger proper the stem E² is pro-

vided with a shoulder e' , adapted to engage the top of the cross-head.

In a machine embracing several plungers, such as is herein shown, the plungers are rigidly connected with each other by means of a transverse bar E^3 , which is located within the hollow interior of the cross-head and is provided with vertical apertures, through which the stems are inserted and in which they are immovably clamped.

O' is a lever pivoted at o upon the lower cross-head and provided with a short arm o^2 , which engages a bearing-recess e^3 in the stem of one of the plungers. As herein shown, Fig. 2, the two outer plunger-stems only are engaged with the guides $O O$, while the lever O' is engaged with the intermediate plunger-stem only. The lever O' is provided with a weight O^3 , said weight tending to depress the outer end of the lever and lift the plungers, and being made of sufficient size to counter-balance the weight of the several lower plungers and connected parts. The said weight O^3 is adjustable upon the lever in order that the lifting effect of the lever may be varied when necessary or desirable for the perfect working of the machine.

P , Figs. 1 and 4, is an adjustable stop located beneath the lever O' , and adapted to limit the downward movement of the same at the time the lower cross-head is at the lower limit of its movement, and to thereby determine the position of the lower plunger within the mold at this time. Said vertically-adjustable stop P is herein shown as formed by or upon the end of a lever P' , which is pivoted in a bracket p upon the frame and the free end or handle of which extends outwardly beyond the frame and has an adjustable connection with a segmental plate P^2 , to which the lever may be clamped for holding the stop in a desired position. Said segment P^2 is herein shown as provided with a slot p' , which is engaged by a clamp-plate p^2 upon the lever; but any other clamping or holding device may be employed. The said plate P^2 is furthermore desirably provided with a scale or graduations by which the position of the lever and the stop carried thereby may be determined by inspection and said stop placed in a desired position.

The several parts above described are so arranged that the lower plunger may be sustained, either by the engagement of the shoulder e' with the top of the cross-head, as illustrated in Figs. 1, 7, and 8, or by means of the weighted lever at the time the cross-head is free from said shoulder, as illustrated in Fig. 6. The weight O^3 is of such size that it will sustain the plungers at times when there is no downward pressure upon the same due to the action of the upper plunger. The parts are so disposed, furthermore, that when the cross-head is at the lower limit of its movement said cross-head will be free from the shoulder e' and the lower plungers will be held up by

the action of the weighted lever, the downward movement of said lever at this time being limited by the stop P , so that the position of the plunger within the mold at the time of filling the same is determined by the position of said stop. It follows that when the lower cross-head is at the lowermost limit of its movement the lower plunger will stand above the bottom of the mold and will be supported in this position by the weighted lever, and the purpose of the adjustable stop P , which engages said lever, is to enable the position of the lower plunger within the mold at the time of filling the same to be changed as desired. Such position of the lower plunger obviously determines the quantity of clay which is fed to the mold by the feed-box. It follows that by changing the position of the stop P at a time when the lower cross-head is at its extreme downward limit of travel the lower plunger may be adjusted within the mold, so that the latter will receive the quantity of clay found desirable or necessary for making bricks of desired thickness, or according to the quality and condition of the clay and other circumstances. When the upper plunger descends into the mold after the latter has been filled with clay, the approach of the upper plunger toward the lower plunger will cause the said lower plunger to recede, the same being sustained at this time solely by the weighted lever. The position of the parts at the time the upper plunger is about to enter the mold is clearly shown in Fig. 6. In the downward movement of the upper plunger the clay will of course be compacted to greater or less extent owing to the action of the weight. When the pressure on the clay exceeds the sustaining-power of the weight, the downward movement of the lower plunger, as the upper plunger descends in the mold, will commence and continue until the shoulder e' strikes the lower cross-head, when said plunger will come to a bearing on the cross-head and its further downward movement will be arrested. The parts are desirably so arranged that the lower plunger will stop at a point near the bottom of the mold, as clearly shown in Fig. 7, which illustrates the position of the parts when the lower plunger has reached the downward limit of its movement.

The upward movement of the lower cross-head for the purpose of more perfectly compressing the brick will preferably begin immediately after the said lower plunger has come to a bearing upon the lower cross-head, at which time the upper plunger will be prevented from descending farther by contact of the cross-head to which said plunger is attached, with the stops b^5 b^6 , and the compression will be completed by the lower plunger, which is then caused to rise by the further straightening of the toggle. The lower plunger will obviously be lifted to bring its upper surface flush with the top of the mold-table by the action of the lower cross-head, and the

upward movement of the lower cross-head is arranged to terminate when the lower plunger reaches the top of the mold. When the plunger reaches the top of the mold, however, the downward strain upon this plunger will be relieved, and inasmuch as the weighted lever is still tending to lift the said plunger, it might throw the same above the mold unless prevented. To prevent such result a stop e^3 is placed on a stem E^2 below the mold-table in position to engage the lower surface of the table or other stationary stop or projection upon the frame when the lower plunger reaches a point at which its top surface is flush with the top of the table. When the weighted lever is arranged to support the lower plunger level with the top of the table, the stop is employed to hold the plunger in this position, as above described, it is obviously not essential that the lower cross-head should remain immovable at the upward limit of its movement for any considerable length of time, inasmuch as the weighted lever will sustain the lower plunger at such upward limit of its movement while the brick is being removed therefrom, even though the lower cross-head begins immediately to descend. It follows that by the use of the weighted lever arranged and operating as described any special construction in the actuating devices of the machine for holding the lower plungers immovable—such, for instance, as the cam-surface upon the lower edge of the beam H , shown in said prior application, hereinbefore referred to—may be omitted. In the use of a weighted lever thus arranged, therefore, the rocking arm J' , made in the form of a gear-segment and engaging a plurality of pins or projections upon the beam, may be employed as the sole means of sustaining the toggle-actuating beam H . The employment of the weighted lever connecting the lower cross-head and the lower plunger or its equivalent, in connection with a stop arranged to limit the upward movement of the lower plunger, is therefore of great importance in a machine of the character herein shown for the reason that it renders unnecessary a careful construction and adjustment of the actuating devices to give the exact movement and dwell at the upward limit of its throw, which would otherwise be required, while at the same time the life of the machine is increased, inasmuch as the wearing parts of the bearing-surfaces, through the medium of which the lower plungers are actuated, will not prevent the successful operation of the machine. Any such wearing of the said parts or bearing-surfaces, in cases where the position of the lower plungers with relation to the table depends solely upon the accuracy of adjustment and form of cam-surfaces or other working parts, will obviously cause the machine to work imperfectly. Another obvious advantage of this arrangement is that the toggles, upper cross-head, and bars do not have to be lifted to so great a height,

as the motion due to the flexing of the toggles, after the lower plungers have been lifted to the top of the table, may all be imparted to the descending lower cross-head, the bars, and the upper toggle-arm. 70

It may sometimes occur that the lower cross-head is not lifted sufficiently to bring the top of the lower plunger exactly flush with the table, while at the same time there is so much frictional resistance to the movement of the parts that the weight will not lift the said lower plunger sufficiently to bring the stop e^3 into contact with the under surface of the table. To provide for such contingency we place upon the lever or weight a set-screw o' , so located that it will strike the under surface of the mold-table, and thereby positively actuate the weighted lever to slightly lift the lower plunger. This set-screw will commonly be so adjusted that it will not strike the table above it; but when, by reason of wear upon the parts or other cause, the lower plunger fails to come exactly flush with the table, the set-screw may be turned up sufficiently to strike the table, and thereby actuate the lever to an extent sufficient to bring the stop e^3 against the bottom of the mold-table. 85

One important advantage gained by the employment of a weighted lever connecting the lower cross-head and plungers arises from the fact that said plungers are thereby rendered adjustable for giving a large or small capacity to the molds without requiring any adjustment of the cross-heads by which said plungers are immediately actuated. In some machines as heretofore made the descent of the lower plungers has been limited by adjustable stops placed upon the frame in position to engage the lower cross-head. In such prior construction it has been found difficult to accurately adjust the stops, as the latter become rapidly worn by the action of the lower cross-head and heavy pressing mechanism thereon. In a machine constructed as herein illustrated any accurate adjustment of the vertical position of the lower cross-head is unnecessary, and elastic stops or cushions may be arranged to receive the impact of the said lower cross-head and parts connected therewith, if desired. In the machine herein illustrated the vertical position of the lower plungers at the time of filling the mold is determined by the position of the adjustable stop P , and said stop, being under the control of the operator, may be shifted to give any desired depth of mold readily at any time, and during any part of the revolution of the machine without regard to the adjustment of the other parts of the machine. 115

We have herein shown the stop P as formed by or upon an oscillating hand-lever P' , but it is entirely obvious that said stop may be sustained upon the frame in any one of many different ways, which will readily suggest themselves to a mechanic. As it relates to and includes said adjustable stop therefore 125

our invention is not restricted to any particular means for supporting or shifting the same. The scale which is provided in connection with a moving part which actuates or 5 moves with the adjustable stop enables the stop to be easily set to give a desired depth of mold without actual measurement of the mold itself, the marks upon the scale corresponding with the depth of mold-cavity, and, 10 in view of the advantages gained by the use of such scale, the latter, when employed in connection with an adjustable stop, is also herein claimed as part of our invention.

In Figs. 2 and 9 we have shown a novel 15 construction in a stop for limiting the downward movement of the lower cross-head, and elastic stops or cushions connected therewith to receive the impact of the said lower cross-head and parts connected therewith. Said 20 stop is placed at the upper end of the machine, adjacent to the pivot G², for reasons that will hereinafter appear. As shown in said figures, the ends of said pivot G² are extended beyond the vertical bars F F, at the 25 outer faces of the same, and upon the ends of said pivots are placed two blocks Q Q, having flat lower faces adapted to engage transverse horizontal stops Q' Q', located upon the frame-standards A² A² below the said blocks 30 Q Q. Said stops Q' Q' are herein shown as formed by integral horizontal ribs cast upon the inner surfaces of the frame-standards. To the lower surfaces of the blocks Q Q are secured cushions g g, of rubber or other suitable material, said cushions, as herein shown, 35 consisting of blocks fitted in recesses in the lower surfaces of the blocks Q Q. The said blocks Q Q are adapted for easy removal from the ends of the pivot-pin G², being for this 40 purpose held thereon by a set-screw q', Fig. 9, or other similar means. When both blocks Q Q are removed, the vertical parts F F and the lower cross-head may be dropped slightly 45 below their normal position and a sufficient distance to carry the top surface of the lower plunger clear of the molds, thereby enabling the lower plunger or plunger-plates to be removed from the machine for renewal or repairs without taking the machine apart. This 50 is an important advantage in machines of this character, for the reason that the taking apart of the machine-frame is a very expensive and troublesome operation.

Q² Q² are removable plates secured in the 55 frame-standards A² A², opposite the blocks Q Q, and adapted to be readily taken off to expose the blocks Q Q when it is desired to inspect or remove the same.

The molds C C of the machine herein shown 60 are provided with side lining-plates c c and end lining-plates c' c', the end lining-plates extending past the ends of the side lining-plates so that all of the lining-plates are held in position by the clamping action of the 65 horizontal bolts b b and of the screw-threaded stems c² c², which are formed upon the parti-

tions C' C', in the same manner described in the said prior application. When this construction is used, the lining-plates may be easily removed from the mold by loosening 70 up the said bolts b b and the nuts upon the stems c² c².

As hereinbefore stated, the adjustable stop for limiting the downward movement of the weighted lever, and thereby controlling the 75 position of the lower plunger within the mold at the time of filling the same, may be mounted upon the frame and adjustably supported in any manner found convenient or desirable. In Figs. 10 and 11 I have shown a construction in the said stop and means for actuating the same having some advantages over that hereinbefore described. As illustrated in said Figs. 10 and 11, R is a horizontal rock-shaft mounted upon the frame-base at the 80 rear of the lower plungers and provided with a crank-arm R', which is located in the path of the weighted lever and serves as a stop for the same. At the end of said shaft R, outside of the frame, a worm-wheel R² is attached to said shaft. R³ is a worm-shaft mounted in suitable bearings at the side of the frame and provided with a worm r, which engages the worm-wheel R². At the upper end of said shaft R³, in position convenient 90 for the operator, is located a hand-crank r'. The face of the worm-wheel R² is desirably provided with an index or scale, and a pointer 95 r² is attached to the frame in position opposite the said index or scale, said scale and pointer serving to indicate to the attendant the exact vertical position of the lever-arm R'. A construction of this kind has the advantage that the stop is always locked securely from movement without any attention 100 on the part of the operator, the worm-wheel being incapable of movement excepting when the worm-shaft is turned.

We have hereinbefore referred to the employment of a spring in place of a weight as 110 a means of movably sustaining the lower plunger from the lower cross-head. A construction of this kind is illustrated in Fig. 12, wherein a lever S is employed, which lever is arranged and operates in the same manner 115 as the lever P'. (Shown in the other figures of the drawings.) In this instance, however, a coiled spring S' is connected with said lever S and with a lug s upon the lower cross-head, said spring acting to pull the outer arm 120 of the lever downwardly, and thereby hold the lower plunger elevated, except when the same is depressed by the action of the upper plunger upon the clay within the mold, in the same manner as hereinbefore described 125 in connection with the weighted lever. A nut s', placed upon the screw-threaded end of the spring S, which passes through the lugs, affords a means of adjusting the tension of the spring. It will of course be seen 130 that the stop P operates in this instance to raise the outer end of the lever against the

action of the spring when the lower cross-head is near the lower limit of its movement, thereby determining the position of the lower plunger within the mold at the time of filling 5 the same, in the same manner as hereinbefore set forth.

In Fig. 13 is illustrated still another construction in devices for yieldingly supporting the lower plunger upon the lower cross-head. 10 In this instance T is a spring placed around the plunger-stem E², between a collar T', affixed on the upper part of the stem, and a cross-piece T² upon the cross-head. U is a set-screw passing vertically through the top of 15 the cross-tree and engaging an arm t upon the collar T'. Said spring serves to lift the lower plunger in the same manner as the weighted lever above described, and the set-screw operates as a stop to determine the position of the plunger within the mold at the time of filling the same in the same manner as hereinbefore stated in connection with the stop P, illustrated in other figures of the drawings.

25 We claim as our invention—

1. The combination, with a mold and plungers working therein, of means for actuating the plungers, embracing toggle-arms connected with the opposite plungers, a crank-shaft, a beam connected with the said crank-shaft and with the middle joint of the toggle-arms, and a shifting fulcrum for the beam, comprising a pivotally-supported arm upon the frame provided with a plurality of bearing recesses or notches, and a plurality of pins or projections upon the beam severally engaging the recesses or notches of said arm, substantially as described.

2. The combination, with a mold and upper and lower plungers working therein, of upper and lower cross-heads connected with the said plungers, vertical slide-bars attached to the lower cross-head, toggle-arms connected with the slide-bars and the upper plunger, a crank-shaft, a beam connecting the middle joint of the toggle-arms with said crank-shaft, a pivot-rod connecting the upper toggle-arms with the vertical slide-bars, removable blocks mounted upon said pivot-rod, and stationary stops upon the machine-frame located in position to engage said blocks for limiting the downward movement of the slide-bars and lower cross-head, substantially as described.

3. The combination, with a mold, of upper and lower plungers sliding therein and means for actuating the lower plunger, having elastic or yielding connection therewith permitting downward movement of said lower plunger relatively to the actuating devices, and stops or shoulders limiting such downward movement or yielding of said plunger with relation to said actuating device, substantially as described.

4. The combination, with a mold, of upper and lower plungers sliding therein, means for

actuating the lower plunger, having yielding connection therewith, stops or shoulders limiting the downward movement or yielding of the plunger, and an adjustable stop limiting the upward movement of the plunger relatively to the parts which actuate the same, substantially as described.

5. The combination, with a mold and upper and lower plungers sliding therein, of means for actuating the lower plunger, comprising a reciprocating cross-head engaged with and supporting the said lower plunger and having sliding connection therewith, and a weighted lever connected with the plunger and lower cross-head and serving to sustain the lower plunger yieldingly in an elevated position relatively to the cross-head, substantially as described.

6. The combination, with a mold, of upper and lower plungers sliding therein, means for actuating the lower plunger, comprising a reciprocating cross-head having sliding engagement with the lower plunger, a weighted lever connecting the lower cross-head with the lower plunger and sustaining the lower plunger yieldingly in an elevated position relatively to the cross-head, and an adjustable stop limiting the movement of the said weighted lever, substantially as described.

7. The combination, with a mold, of upper and lower plungers sliding therein, means for actuating the lower plunger, having yielding connection therewith, an adjustable stop limiting the upward movement of the lower plunger relatively to the actuating devices, and a scale or index marked to indicate the depth of mold as determined by the position of said adjustable stop, substantially as described.

8. The combination, with a mold and lower cross-head, of a lower plunger which is movable vertically with relation to the cross-head, and a weighted lever pivoted upon the cross-head and acting upon the plunger, said lever being provided with a vertically-adjustable stop limiting the upward movement of the lever by contact with an adjacent part of the machine-frame, whereby the lower plunger may be brought flush with the top of the mold, substantially as described.

9. The combination of a mold and upper and lower plungers working therein, and means for actuating the plungers, comprising toggle-arms connected with both plungers and with the lower plunger by an elastic or yielding connection allowing a limited downward movement of the said lower plunger relatively to the toggle-arms connected with it, a crank-shaft, a beam connected with said crank-shaft and with the middle joint of the toggle-arms, and a pivotally supported or notched arm upon the machine-frame, said beam being provided with a plurality of pins or projections engaging the notches of said arm.

10. The combination of a mold, upper and lower plungers, toggle-arms connected with

both plungers and movable vertically at both ends with the plungers, a toggle-operating beam fulcrumed between its ends and connected with the central joint of the toggle, 5 and a stationary stop or stops located in position to engage the upper plunger and limit the descent of the same, and thereby operating to determine the vertical position of the plungers within the mold at the time of greatest compression, substantially as described.

In testimony that we claim the foregoing as our invention we affix our signatures in presence of two witnesses.
